UNITED STATES PATENT OFFICE.

BENJAMIN J. SEXAUER AND HENRY C. SCHULTZ, OF CHICAGO, ILLINOIS.

EDGE-FOLDING MACHINE.

1,262,855.

Specification of Letters Patent. Patented Apr. 16, 1918.

Application filed June 2, 1917. Serial No. 172,875.

To all whom it may concern:

Be it known that we, BENJAMIN J. SEXAUER and HENRY C. SCHULTZ, both citizens of the United States, and both residents of Chicago, county of Cook, and State of Illinois, have invented certain new and useful Improvements in Edge-Folding Machines, of which the following is declared to be a full, clear, and exact description.

10 This invention relates to edge folding machines, and its primary object is to provide a machine, automatic in its operation, and having co-acting edge folding and clenching devices operating to fold and clench the edge 15 of a sheet of foraminated or reticulated metal, such as wire mesh material. It has been designed particularly for bending or folding down the edges of wire screen material in the manufacture of "fly swatters" 20 but it may be used for a great variety of purposes. The invention consists in the several novel features hereinafter fully described and particularly pointed out in the claims.

25 The invention is clearly illustrated in the accompanying drawings, in which— Figure 1 is a plan of an edge folding machine embodying a simple form of the present invention with a certain table removed; Fig. 2 is a side elevation thereof with part of the table broken away; Fig. 3 is a vertical cross section taken on line 3—3 of Fig. 1; Fig. 4 is a rear view of a fragment of the machine looking in the 30 direction of the arrow 4 in Fig. 1; Fig. 5 is a front elevation of the machine looking in the direction of the arrow 5 in Fig. 1; Fig. 6 is a plan of a fragment of a movable clenching jaw; Fig. 7 is a detail cross section through the edge folders, showing a 35 piece of wire fabric in place on the table; Fig. 8 is a view similar to Fig. 7, except that the edge folder is in the position occupied when the fold is made; Fig. 9 is an 40 edge view of the fabric after the fold has been made; Fig. 10 is an edge view of said fabric after the clenching or closing operation has been performed.

Referring to said drawings, 10 designates 45 a base plate, and 11 two end pieces that extend up from the ends of said base plate. Said end pieces are slotted in a plane at right angles to the base plate for the reception of a lengthwise extending bar 12, which 50 has a comparatively thin lower edge portion 13, and comprises the edge folder of the

machine. In the operation of the machine said bar is reciprocated toward and away from the base plate 10, as will be herein-after set forth. Supported upon the base 60 plate 10, is a bar 14, which extends lengthwise of the base plate and is located adjacent the path of movement of bar 12; said bar 14 provides a stationary clenching jaw, which co-acts with a movable bar 17 to 65 clench together the two parts of the folded edge. Said movable bar 17, comprises a clenching jaw which is supported by the base plate 10 and extends parallel with the bar 14, and is normally spaced therefrom to 70 permit the thin edge 13, of the folder 12 and the fabric to pass therebetween. Two guide blocks 16 are secured to the base plate 10, and have notched portions 15, in which are guided the outer ends of the movable jaw 75 17. The movable jaw is reciprocated toward and away from the stationary jaw 14, by a mechanism which will be presently described.

Journaled in the end pieces 11, is a shaft 80 18, which is driven by any suitable means and to said shaft are secured two folder actuating arms 19, which are arranged to strike against shoulders 20 secured to and projecting rearwardly from the folder 12. 85 Said shoulders may comprise blocks fastened to the rear face of the folder 12. The proportions of these parts are such that during a revolution of the shaft 18, the arms 19, force the folder 12 down from the position 90 seen in Figs. 3 and 7 to that seen in Fig. 8, at which time the arms 19, leave the shoulders 20, and permit the folder 12, to be raised. Below the shaft 18 is a rock shaft 95 21, which is journaled in the end pieces 11, and has two upwardly projecting arms 22 secured thereto, which arms engage with the undersides of shoulders 23, (see Fig. 3) which project rearwardly from the folder 12. A coiled spring 24, encircles the shaft 100 21, and has one end secured to said shaft and the other end secured to the adjacent end-piece 11. Said spring operates to swing the arms 22, in the direction of the arrow thereon in Fig. 3, thereby returning the folder 12, 105 to its upper or former position. It sometimes happens that the woven fabric becomes wedged between the thin portion of the folder 12 and the jaws 14 and 17 and means are provided for positively lifting 110 the folder out of its engagement with said fabric. In the form shown in the drawings,

said means comprise an arm 25, secured to the shaft 18, and an arm 26, secured to the rock shaft 21, and lying in the path of rotation of the arm 25. The parts are so timed 5 that after the arms 19 have lowered the folder 12, the arm 25, is in position to engage the arm 26, and turn the rock shaft 21, in the direction indicated by the arrow in Fig. 3 sufficiently to disengage the thin portion 13, 10 of the folder 12, from the fabric which it has folded; thereafter the spring 24, acts to return the folder 12 to its former position. A bar 11^a, secured to the end pieces 11, limits the upward movement of the folder 12. 15 The means for reciprocating the movable jaw 17, may comprise lugs 27, secured to the shaft 18, levers 28, lying in the paths of movement of said lugs and pivoted at their lower ends to the end pieces 11, and links 20 29, connected to said levers 28, and to the movable jaw 17 by screws or rivets 30, 31. The upper end of the levers 28, are in the paths of movements of the lugs, and once 25 during each cycle of revolution of the shaft 18, said lugs 27, engage the levers 28, and swing them in the direction of the arrow thereon in Fig. 2, thereby drawing the bar 17 toward the bar 14. Coiled tension springs 32, are secured to the levers 28, 30 by pins or rivets 33, and also secured by the base plate 10 by pins 34, and said springs 32, act to return the levers 28, and therewith the links 29, and movable jaw 17 to former position. A guide bar 36 is secured to the 35 stationary jaw 14, and fixes the location of the edge to be folded.

We have found that the best results are obtained by feeding the material which is to be folded toward the folding devices at an 40 angle of approximately 45 degrees, and have shown a table, 35, located in front of the folding devices, and extending at an angle of approximately 45 degrees thereto; said table may be secured to the base plate 45 or to any other accessible portion of the machine.

In the operation of the device, the shaft 18, is rotated in the direction of the arrow, in Fig. 3, either continuously or intermittently 50 one revolution at a time. The sheet of fabric A, to be operated on, is placed on the table 35 with an edge parallel with the folders, and moved along the table until said edge strikes the guide bar 36. During one 55 revolution of the shaft 18, the arms 19 first encounter the shoulders 20 of the folder 12, (see Fig. 3) and move the latter down to the position shown on Fig. 8, thereby folding up the edge as shown in said Fig. 8 and 60 in Fig. 9. During the downward movement of the bar 12, the arms 22 are swung down and the rock shaft 21 turned part way around in a direction opposite the arrow in Fig. 3, thereby winding up the spring 65 24. When the bar reaches its lower-most

position the arms 19 ride off the entire shoulders 20, and the spring 24 turns the shaft back and therewith the arms 22 which raise the folder 12. In case the folder is wedged between the jaws 14, 17, the arm 25 strikes the arm 26 on the shaft 21 and turns said shaft and therewith positively lifts the folder 12 by means of the arms 22. Immediately after the lower edge portion 13 of the folder 12 has risen above jaws 14, 17, the lugs 27 strikes the levers 28, swing them in the direction of the arrow thereon in Fig. 2, thereby drawing the links 29 and jaw 17 toward the right as viewed in said Fig. 2 and thereby clenching the folded edge 80 against the adjacent part of the fabric. When the lugs 27 have passed the levers 28, the springs 32 return the levers 28 and therewith the links 29 and jaw 17 to normal position. 85

More or less variation of the exact details of construction is possible without departing from the spirit of this invention; we desire, therefore, not to limit ourselves to the exact form of construction shown and 90 described, but intend in the following claims to point out all of the invention disclosed herein. 95

We claim as new and desire to secure by Letters Patent:

1. In a machine for folding and clenching down edges of metal sheets, a pair of clenching jaws having straight faces, and one movable toward and away from the other, an edge folder having a comparatively thin edge folding portion, and movable at right angles to the plane of movement of said jaw from an inoperative position to one between the jaws, a single rotatory shaft having means thereon directly 100 engaging said edge folder and arranged to depress the same, a rock shaft having means thereon directly engaging said edge folder, and moved in one direction thereby, a spring for turning said rock shaft in a direction 110 opposite to that imparted to it by the downward movement of the edge folder, links secured to said movable jaw, lugs on said rotatory shaft for moving said links, and therewith said movable jaw in one direction, 115 and springs for retracting said links and jaw.

2. In a machine for folding and clenching down edges of metal sheets, a reciprocatory edge folder having a thin edge portion, 120 guide members in which said folder is guided, a pair of clenching jaws having flat working faces, one of said jaws being movable toward and away from the other jaw in a plane transverse to the plane of movement of said folder, a rotatory shaft, a plurality of arms secured to said shaft adjacent the ends of said edge folder and arranged to engage the upper sides of shoulders on said folder and thereby move said folder 125 130

toward and between said jaws, a rock shaft, a plurality of arms secured thereto and engaging the under sides of shoulders on said folder, a coiled spring surrounding said 5 rock shaft and acting to turn said rock shaft and thereby move the arms thereon, and therewith the folder away from the jaws, links connected to the ends of said movable jaw, levers connected to said links, 10 lugs on said rotatory shaft arranged to strike said levers and thereby move said levers, links and movable jaw to clench down the folded edge of the material, and springs secured to said levers for retracting 15 the same.

3. In a machine for folding and clenching down edges of metal fabrics, a reciprocating edge folder having a thin edge folding

portion, a pair of clenching jaws, one of which is movable in a plane at right angles 20 to the plane of movement of the folder, the thin portion of said folder being movable into the space between the jaws, folder actuating mechanism and jaw actuating mechanism comprising a single rotatory shaft 25 having lugs thereon arranged to engage and depress the edge folder; and other lugs thereon, links connected to the clenching jaw, and levers connected to the links and extending into the paths of movement of 30 the last mentioned lugs, and a table arranged to support the sheet to be operated on, at an angle of approximately 45 degrees to the planes of movement of the folder and jaw.

BENJAMIN J. SEXAUER.
HENRY C. SCHULTZ.
